Ex
O 11,306

No. 11306.

July 29- 1879

UNITED STATES PATENT OFFICE.

SIGMUND FEUST AND JULIUS NEUMANN, OF NEW YORK, N. Y.

DESIGN FOR BUREAUS.

Specification forming part of Design No. **11,306**, dated July 29, 1879; application filed June 2, 1879.
[Term of patent 3½ years.]

To all whom it may concern:

Be it known that we, SIGMUND FEUST and JULIUS NEUMANN, of the city, county, and State of New York, have invented a new and original Design for Tops for Articles of Furniture, of which the following is a full, clear, and exact description, reference being had to the accompanying photographic illustration, making part of this specification.

This invention relates to an improved design for the tops of bedsteads, dressers, washstands, and other articles of furniture; and consists of a supporting-cornice, of a main railing, and of a center panel crowned by a supplementary cornice and top railing.

Referring to the illustration, A represents the top cornice of a bedstead, dresser, washstand, or other article of furniture; and B, a railing that extends over the cornice, and which is finished at both ends by quadrantal pieces *a a*. A center panel, C, rises from a channeled quadrantal center portion, A', of the cornice, and extends to some distance above the railing. The center panel is ornamented by a raised filler and corner rosettes. The center panel, C, is surmounted by a supplementary cornice, D, which projects boldly from the panel and carries a top railing, E. From the

upper corners of the center panel, C, extend symmetrical ornaments *b*, that serve to fill up the angles between main railing and panel, so as to form connecting members between the railing and panel, and render the springing out of the supplementary cornice less abrupt.

The design of the top is of a unique and striking character, yet, owing to the railings, of light and elegant appearance.

What we claim as new, and desire to secure by Letters Patent, is—

The design for a top for articles of furniture, consisting of a supporting-cornice, of a main railing with quadrantal terminals, of a raised center panel extending from a channeled quadrantal center portion of the cornice, of a supplementary cornice and top railing, and of filling ornaments at both sides of the center panel, as shown and described.

In testimony that we claim the foregoing as our invention we have signed it this 29th day of May, 1879.

SIGMUND FEUST.
JULIUS NEUMANN.
